JAMES MITCHELL, OF LA PORTE, INDIANA.

Letters Patent No. 72,069, dated December 10, 1867.

IMPROVED CAR-BRAKE.

The Schedule referred to in these Letters Patent and making part of the same.

TO ALL WHOM IT MAY CONCERN:

Be it known that I, JAMES MITCHELL, of La Porte, in the county of La Porte, and State of Indiana, have invented a new and useful Improvement in Car-Brakes; and I do hereby declare that the following is a full, clear, and exact description of the same, reference being had to the annexed drawings, making part of this specification, in which—

Figure 1 is a plan,

Figure 2 is a vertical section, and

Figure 3 is a horizontal section on line $z-z$, and plan of the lower part of the mechanism.

The same letters employed in the several figures indicate the same parts.

The mechanism is intended to operate automatically after being wound up by means of the lever A acting upon the reciprocating connecting-rod B, which is attached to the long arm of a lever, C, pivoted at C'. To this lever are pivoted the pawls D and D', one on each side of the fulcrum C', and connected by a spiral spring, D'', extending from the point of one to the heel of the other, so that by its tension it will draw the points of both the pawls against the teeth of the ratchet-wheel E. The ratchet-wheel E is attached to the shaft E', the toe of which rests in the upper end of the shaft I. It is bolted to the plate-wheel E'', which has a notch in its edge at E''. When the action of the lever upon the pawls has caused the wheel E and plate E'' to revolve so that the stop-lever G, which is pivoted at the centre to the cross-brace H, shall catch into the notch E'', it will be drawn into the notch by the tension of the spring G'. The pawls may now be disengaged by throwing the lever A back far enough to do so; but in order that this may not occur before the lever G has engaged the notch E'', a pin, A', is passed through the guard, confining the lever, so as to limit its oscillation, as shown in fig. 1, within the space requisite for keeping the pawls in action. By this action of the lever the chain K is drawn back with the revolution of the wheel E'', to which it is attached by a wrist, K', on the wheel. A pin, E'', on the ratchet-wheel striking against the brace F, regulates the revolution of the wheel in that direction, the brace being cut away on the other side, so that the pin E'' will pass under it. The chain, as drawn back, brings with it the yoke L, enclosing and bearing against one of a series of springs, M, which are compressed as the lever A is oscillated, storing the force necessary to apply the brakes to the wheels, when the catch-lever G, by which the wheel E'' is held in place, is detached.

This is accomplished in the following manner: N is a cord intended to be extended from the locomotive to all the brakes. This cord is attached to the long arm of a lever, O. The short arm of this lever forms a pinion acting upon the cogs on the side of the reciprocating ratchet-bar P, which extends past the lever G, and in such relation thereto that an inclined notch must be cut out of the side thereof, to allow it to pass the lever. When the ratchet-bar P is moved by the action of the lever O, the inclined face P' pressing against the lower end of the lever G, (which is pivoted at the middle,) will throw the upper end thereof out of the notch E'', and thus disengage the wheel E'', which, with its shaft E', will be caused to revolve by the tension of the springs M. The brakes Q are connected by the rods Q' with the arms Q'' upon the lower end of the shaft I, and are drawn against the wheels by the revolution of that shaft. The shafts E' and I are locked together by the following means: The collar R is attached to the shaft E'. The arm R' is pivoted to lugs extending from the collar R. The spring R'' presses against the lower end of the arm R'. The collar S is fastened to the upper end of the shaft I. Its periphery is spiral, so as to form a notch or shoulder against which the arm R' will catch as the shaft E' is turned, in the manner set forth, so that when the wheel E'', having been wound up, is disengaged, as explained, the arm R', bearing against the shoulder of the collar S, will cause the shaft I to revolve with the shaft E', thereby drawing the brakes Q against the wheels with the full power of the springs M.

The brakes may be released in the following manner: The ratchet-lever P has a shoulder formed at P' by cutting away the top part of the lever T, the end of which is drawn upwards and back by the spring T'. The opposite end of this lever rests upon the spiral collar U on the shaft I. When this shaft is turned by the means set forth, the inclined face of the collar U will turn up the end of the lever T, which rocks upon its pivot, so that on the return of the ratchet-bar P it should fall below the shoulder P'. When the arm R' revolved with the shaft, it was carried against the lever T. Now, by moving the ratchet-bar P, by the means explained, a second time, the shoulder P' will draw with it the end of the lever T, thereby pressing the other end of the lever out against the hinged arm R', which may be thereby forced outwardly, so as to disengage the collar S, against

the shoulder of which it presses. As soon as that is done, the spring V will cause the shaft I to return to its normal position, thereby releasing the brakes.

The mechanism must again be wound up by means of the bar A, as set forth.

What I claim as my invention, and desire to secure by Letters Patent, is—

1. The combination of the lever A, rod B, lever C, pawls D and D¹, spring D², and ratchet-wheel E, substantially as and for the purpose set forth.

2. The combination of the shaft E³, collar R, arm R', collar S, and shaft I, substantially as set forth.

3. The combination of the shaft I, spiral collar U, lever T, and arm R, for disengaging the brakes, substantially as set forth.

4. The combination of the ratchet-bar P with the inclined face P¹ and catch-lever G, substantially as and for the purpose set forth.

5. The combination of the ratchet-bar P with its shoulder P² and the lever T, substantially as and for the purpose set forth.

In testimony whereof, I have signed my name to this specification in the presence of two subscribing witnesses.

JAMES MITCHELL.
